Primary Examiner — Bao-Yen T Nguyen(74) *Attorney, Agent, or Firm* — Venable LLP(57) **CLAIM**

The ornamental design for a strobe for camera, as shown and described.

DESCRIPTION

FIG. 1 is a Front view of a strobe for camera showing our new design;

FIG. 2 is a Back view thereof;

FIG. 3 is a Top view thereof;

FIG. 4 is a Bottom view thereof;

FIG. 5 is a Left side view thereof;

FIG. 6 is a Right side view thereof; and,

FIG. 7 is a Perspective view thereof.

The dashed broken lines show portions of the strobe for camera that form no part of the claimed design. The dashed-dotted broken lines define a boundary of the claimed design and form no part of the claimed design.

1 Claim, 7 Drawing Sheets(56)
